UNITED STATES PATENT OFFICE.

HENRY P. CLAUSEN, OF MOUNT VERNON, AND CHARLES L. GOODRUM, OF BROOKLYN,
NEW YORK, ASSIGNEES TO WESTERN ELECTRIC COMPANY, INCORPORATED, OF NEW
YORK, N. Y., A CORPORATION OF NEW YORK.

TELEPHONE SYSTEM.

1,287,886.

Specification of Letters Patent. Patented Dec. 17, 1918.

Application filed October 6, 1916. Serial No. 124,073.

To all whom it may concern:

Be it known that we, HENRY P. CLAUSEN and CHARLES L. GOODRUM, citizens of the United States, residing at Mount Vernon, in the county of Westchester and State of New York, and at Brooklyn, in the county of Kings and State of New York, respectively, have invented certain new and useful Improvements in Telephone Systems, of which the following is a full, clear, concise, and exact description.

This invention relates to telephone systems, and especially to means for preventing wrong connections by reason of false impulses caused by the careless manipulation of the calling substation apparatus.

It has been found in practice that the calling subscriber, by carelessly removing his receiver from the switchhook, interrupts the line circuit in a manner similar to the interruptions of the dial switch. It frequently results that one or more impulses may thus be transmitted to the first selector switch, thereby operating the switch so that it is not in the proper position to receive the first series of directive impulses. If the directive impulses of the dial switch are transmitted following such false impulses, a wrong connection will be established.

It is the object of this invention to provide means to prevent such false impulses from misplacing an automatic switch.

One feature of this invention is the use of electrical means to restore an automatic switch if it has been misplaced, as above described.

Another feature of this invention is the provision of mechanical means to restore the switch to normal position if it has been misplaced.

Other features of this invention will appear from the detailed description and claims.

Referring to the drawings, Figure 1 represents diagrammatically a portion of a telephone system employing the present invention. The portion of the diagram included within the dotted rectangle represents the apparatus individual to the subscribers' lines. At the right of the drawing there is indicated a first selector and its operating circuit.

Fig. 2 is a perspective view of a portion of a selector or numerical switch employing

means for restoring the switch if it is misplaced. Certain mechanical parts and the operating circuits have been omitted from this showing for clearness in illustration.

Referring to Fig. 1, the mechanism within the dotted rectangle includes a line switch 60 of the type disclosed in patent to A. E. Keith, No. 1,078,685, November 18, 1913, and the patent to Setter, No. 1,104,451, July 21, 1914. In the line switch disclosed in the above mentioned patents, there is a plunger 65 or contact operating device which is individual to each of the lines of the group. A master switch is provided to maintain the plungers of non-calling lines in a position such that upon their operation, they will 70 connect the calling line to an idle trunk.

When the subscriber at substation A removes his receiver from its switchhook, line relay 1 is energized over a circuit which may be traced from grounded battery, back contact and left-hand armature of cut off relay 2, upper side of the line, through the substation apparatus, lower side of the line, back contact and right-hand armature of cutoff relay 2, right-hand winding of line relay 1 80 to ground. Relay 1 is energized and attracts its armature. This completes an operating circuit for the plunger operating magnet 3, which circuit may be traced from grounded battery, right-hand winding of magnet 3, 85 front contact and armature of relay 1 to ground. Magnet 3 is energized and its plunger 4 forces the switch springs 5 into engagement with the terminals of an idle trunk. This completes an energizing circuit 90 for the cutoff relay 2 which may be traced from grounded battery, left-hand winding of magnet 3, relay 2, lower line switch spring 5, lower side of the trunk, relay 6, back contact and armature of release magnet 9 to 95 ground. Cutoff relay 2 operates in the well-known manner to disconnect the line relay 1 from the talking circuit.

Simultaneously relay 6 attracts its armatures, and places ground on the master switch contact 20' in the well-known manner. At the outermost armature of relay 6 a break point in the release circuit is closed. This release circuit will be hereinafter described.

When the switch springs 5 are forced into 105 engagement with the trunk terminals, stepping relay 8 of the first selector is energized over a circuit which may be traced from

grounded battery, relay 8, side switch arm 20 in its first position, upper side of the trunk, upper switch spring 5, front contact and left-hand armature of cutoff relay 2, 5 upper side of the line, through the substation apparatus, lower side of the line, front contact and right-hand armature of cutoff relay 2, lower switch spring 5, lower side of the trunk, relay 6, back contact and armature of release magnet 9 to ground. Stepping relay 8 attracts its armature and closes a break-point in the energizing circuit of the slow-releasing relay 10, which circuit may be traced from grounded battery, relay 10, 10 back contact and armature of the test relay 11 to ground.

During the interruptions of the line circuit, caused by the operation of the dial switch sender or in response to uniformly timed impulses of current from any suitable source, stepping relay 8 is intermittently de-energized and energized, and its armature thereby caused to vibrate. Relay 10, being slow to release, does not retract its armatures during the resulting momentary interruptions of its energizing circuit.

At the first deenergization, the stepping relay 8 retracts its armature and completes an energizing circuit for the second slow release relay 12. This circuit may be traced from grounded battery, relay 12, front contact and left-hand armature of relay 10, back contact and armature of stepping relay 8, back contact and armature of test relay 11 35 to ground. Relay 12 attracts its armature and completes an operating circuit for escape magnet 13, which circuit may be traced from grounded battery, escape magnet 13, front contact and armature of relay 12 to ground. Relay 12 attracts its armature and completes an operating circuit for the primary magnet PM, in parallel with the energizing circuit of relay 12, extends from grounded battery, primary magnet PM, front contact and left-hand armature of relay 10, back contact and armature of relay 8, back contact and armature of test relay 11 40 to ground. An operating circuit for the primary magnet PM, in parallel with the energizing circuit of relay 12, extends from grounded battery, primary magnet PM, front contact and left-hand armature of relay 10, back contact and armature of relay 8, back contact and armature of test relay 11 45 to ground. An operating circuit for the primary magnet PM, in parallel with the energizing circuit of relay 12, extends from grounded battery, primary magnet PM, front contact and left-hand armature of relay 10, back contact and armature of relay 8, back contact and armature of test relay 11 to ground.

In response to impulses from the dial switch the primary magnet PM operates the switch the prescribed number of steps, corresponding to the first digit of the desired number. At the close of the first series of impulses, stepping relay 8 attracts its armature for a relatively long interval and therefore by interrupts at its back contact the energizing circuit for the slow releasing relay 12. Relay 12 retracts its armature and breaks the operating circuit for the escape magnet 13. The escape magnet, on its deenergization, moves the side switch wipers into their second position.

An operating circuit for the secondary magnet 15 is now completed, which circuit may be traced from grounded battery, secondary magnet 15, armature of magnet 15,

side switch wiper 16 in its second position, front contact and armature of relay 8, back contact and armature of relay 11 to ground. The secondary magnet operates to cause the switch brushes 22 and 23 to traverse the terminals 24 and 25 of the trunks terminating in the bank. The terminals of the busy trunks traversed by the lower switch brush 23 are provided with raised potential so that the test relay 11 will not be energized. 75 When, however, the switch brushes engage the terminals of an idle trunk, relay 11 will pull up, interrupting the circuit for the stepping magnet 15. The energization of test relay 11 completes an energizing circuit for 80 the escape magnet which extends from ground, armature and front contact of relay 11, front contact and right-hand armature of relay 10, escape magnet 13 to grounded battery. The escape magnet is energized and 85 moves the side switch wipers into their third position, in a manner which is clearly disclosed in the patent to C. L. Goodrum No. 1,231,013, June 26, 1917.

As the operation of the switches succeeding the first selector may be of substantially the same character as that shown in the patent to C. L. Goodrum No. 1,251,503, Jan. 1, 1918, the operation of establishing the rest of the connection will not be described. 90

Before the side switch wipers move into their third position, the deenergizations of the stepping relay 8 are momentary in duration. Slow-releasing relay 10, therefore, remains energized and holds open the operating circuit of the release magnet 9, which circuit may be traced from grounded battery, release magnet 9, outermost armature and front contact of relay 6, side switch wiper 18, back contact and left-hand armature of relay 10, back contact and armature of relay 8, and back contact and armature of relay 11 to ground. If the calling party should abandon the call by interrupting the substation circuit, after a series of impulses 100 is sent, stepping relay 8 will retract its armature, thereby causing the deenergization of relay 10 and the completion of the release circuit as described.

At the time the side switch moves out of 115 position 2, and the stepping relay 8 deenergizes, the relay 11 as described is energized. When, however, the side switch reaches position 3, relay 11 becomes deenergized, due to certain changes at the succeeding selector switch, thus opening a release circuit which would otherwise be completed from ground, front contact and armature of test relay 11, back contact and right-hand armature of relay 10, side switch wiper 18 120 in its third position, outermost armature and front contact of relay 6, release magnet 9 to ground. At the termination of the conversation, relay 11 becomes energized, due to certain changes at the succeeding switch, 125 130

in a manner which will be well understood from the above mentioned Patent No. 1,251,503.

Should the calling party, after the operation of the line switch, replace his receiver on the hook without operating the dial switch, the stepping relay 8 will become de-energized, thereby completing a circuit for the release magnet 9. This circuit may be traced from grounded battery, release magnet 9, front contact and outermost armature of relay 6, and back contacts and armatures of relays 10, 8 and 11 to ground, as previously described. The operation of release magnet 9 interrupts the circuit of relays 6 and 2 and magnet 3. If the switch has moved from its normal position, release magnet 9 establishes a holding circuit for itself, which extends from grounded battery, magnet 9, off-normal contact 17, front contact and armature of relay 9 to ground.

The deenergization of magnet 3 allows the plunger 4 to be retracted. The armatures of cutoff relay 2 are retracted and connect the subscriber's line to his line relay 1. The retraction of the armatures of relay 6 removes the busy potential from the bank contact 20 of the master controller, thus permitting the trunk to again be selected.

In the preceding description it is assumed that the calling party did not send any false impulses by the careless removal of his receiver from the switchhook.

Assuming now that the subscriber raises his receiver and then allows it to drop back on the switchhook before he finally removes it for use, the quick-operating line switch will connect the calling substation to an idle trunk, and when the receiver falls back on the switchhook, an impulse similar to those transmitted by the dial switch will operate the selector switch one step forward in a manner previously described. If the calling party now sends impulses corresponding to the first digit of the desired line, the switch will be wrongly positioned, and a wrong connection will result.

The purpose of the present invention is to avoid the misplacement of the switch, by reason of false impulses caused by the careless removal of the receiver. In this arrangement, if a single impulse is sent, followed by a time interval of sufficient length to permit the side switch to move into position 2, the switch will then proceed to hunt for an idle trunk in the well-known manner. When the switch has taken a single primary step, and proceeds in its hunting operation, an off-normal contact 19 will be closed to ground, thereby completing a release circuit which may be traced from grounded battery, release magnet 9, off-normal contact 19 to ground. This will restore the first selector switch to normal position, whereupon it will be in condition to receive the

impulses from the dial switch. For convenience in description, it has been assumed that the apparatus will be designed to intercept one false impulse. It will be understood, however, that the apparatus may be arranged to intercept two or more false impulses by properly positioning the off-normal contact 19.

Referring to Fig. 2, the selector switch herein disclosed is of the type shown in U.S. Patent 831,875. It will be understood, however, that the present improvement may be employed in other switches, in which the brushes are positioned through two series of movements.

It will be noted that the switch structure shown in this figure can be used in the selecting circuit arrangement shown in Fig. 1 if the off-normal contact 19 is not utilized.

In the present disclosure 50 designates a brush shaft mounted for rotary movement in a supporting structure (not shown). This shaft carries brushes 51, which engage the passive contacts of a switch bank 52. The brushes 51 are so positioned with respect to the passive contacts with which they co-operate, that it is necessary for the brushes to be elevated two vertical steps before they are in operative relation to the first group of terminals of the switch bank. When, however, this switch is employed in the system such as that shown in Fig. 2, it will be understood that only two of the brushes 51 and their corresponding contacts will be necessary. The shaft at its intermediate portion 100 is provided with vertical ratchet teeth 53, which are adapted to be engaged by the vertical pawl 54, carried by a pivoted arm controlled by the armature of motor magnet 55. The shaft is also provided with rotary 105 ratchet teeth 56, which are adapted to be engaged by the rotary pawl 57. This pawl is also carried by a pivoted arm which is controlled by the armature of the rotary magnet 58.

59 designates a frame which is pivoted on the vertical rod 60. This frame is provided with a vertical holding dog 61, and a rotary holding dog 62. The frame 59 is also provided with an angular extension 63, the purpose of which will be hereinafter described. The frame 59 is secured to the armature of the release magnet 65, and it will be understood that when the release magnet 65 is energized, the holding dogs 61 and 62 will be disengaged from the vertical and rotary ratchet teeth, allowing the shaft to be restored to its normal position.

The shaft 50 carries a pin 64 which is adapted to engage the angular extension 63 when the shaft is elevated a prescribed number of steps, and then proceeds in its hunting operation.

Referring to the operation of the switch, when the directive impulses of the dial

switch are transmitted to the selector, the vertical magnet 55 attracts its armature, in response to these impulses, and the vertical pawl elevates the shaft the prescribed number of steps to position the brushes 51 before a group of trunks, whose terminals are indicated in terminal bank 52. A holding dog 61, which normally engages the vertical ratchet teeth in the shaft, serves to hold the shaft in the position to which it has been elevated.

At the termination of the first series of impulses, an escape magnet (not shown) interrupts the operating circuit of the primary magnet and completes a self-interrupting circuit for the rotary magnet 58. This magnet attracts its armature and thereby actuates the rotary pawl 57 to place the brushes 51 on the terminals of the idle trunk. The rotary holding dog 62 operates to hold the shaft in its actuated position.

At the close of the conversation, release magnet 65 is energized in the well-known manner, and attracts its armature. This operation disengages the vertical holding dog 61 and the rotary holding dog 62, so that the shaft may be restored to its normal position.

If the shaft is elevated a predetermined number of steps, in the case of this disclosure, a single vertical step, and the shaft is then rotated during the hunting operation of the switch, the pin 64 will engage the angular extension 63. This will force holding dogs 61 and 62 out of engagement with the vertical and rotary ratchet teeth, and permit the switch to be restored to its normal position.

It will be understood that this disclosure is merely illustrative of applicants' improvement and the present invention will be limited only by the appended claims.

What is claimed is:

1. In a telephone system, an incoming line, an outgoing line, a switch operating through movements in two directions to interconnect said lines, means for operating said switch, means for automatically releasing said switch at the initiation of movement in one direction after predetermined movements in the other direction.

2. In a telephone system, an incoming line, an outgoing line, a switch operating through selecting and hunting movements to interconnect said lines, means for operating said switch, and means for automatically releasing said switch at the initiation of the hunting movement after predetermined selecting movements.

3. In a telephone system, an incoming line, an outgoing line, a switch for interconnecting said lines, means for imparting to said switch movements of two different characters, and means for automatically releasing said switch after a predetermined degree of

movement of each character which is less than its maximum movement.

4. In a telephone system, an incoming line, an outgoing line, a switch for interconnecting said lines, means for operating said switch, releasing means for said switch, and means for automatically rendering said releasing means effective if the switch is operated a prescribed number of steps in two directions, which is less than the greatest number of steps the switch is capable of being moved.

5. In a selecting switch, active contacts, passive contacts, a shaft to which said active contacts are secured, means for operating said shaft through movements in two intersecting planes, holding means to maintain said shaft in the position to which it has been actuated in its two movements, and means directly controlled by said shaft to disengage said holding means under predetermined conditions.

6. In a selecting switch, passive contacts, active contacts, a shaft to which said active contacts are secured, means for operating said shaft in two different directions, holding means to maintain said shaft in the position to which it has been actuated in its two movements, and means carried by said shaft to disengage said holding means under predetermined conditions.

7. In a selecting switch, passive contacts, active contacts, a shaft to which said active contacts are secured, said shaft being mounted for movement in two directions, holding dogs to maintain said shaft in the position to which it has been actuated in its two movements, and means operated by said shaft under predetermined conditions to disengage said holding dogs.

8. In a telephone system, an incoming line, outgoing lines, a switch for interconnecting said incoming line with any of said outgoing lines, and means responsive only to a plurality of impulses of current for directly operating said switch.

9. In a telephone system, an incoming line, a plurality of outgoing lines, a switch for interconnecting said incoming line with any of said outgoing lines, means responsive only to a plurality of impulses from a distant point for directly operating said switch.

10. In a telephone system, an incoming line, a plurality of outgoing lines, a switch for interconnecting said incoming line with any of said outgoing lines, said switch being controlled by impulses of current, and means for rendering said switch selectively non-responsive to a single impulse of current.

11. In a telephone system, an incoming line, a plurality of outgoing lines, a switch for interconnecting said incoming line with any of said outgoing lines, a device associated with said incoming line for transmitting a plurality of impulses to directly 125

operate said switch, and means for rendering said switch selectively non-responsive to a single impulse of current.

12. In an automatic telephone system, the combination of an impulse transmitter, an impulse-responding device, and means responsive to the operation of said device for automatically re-setting the device when only one impulse is received by it.
13. In a telephone system, the combination with a telephone line extending from substation apparatus to main station apparatus, a circuit interrupter and a switch for the said substation apparatus, a step-by-step switch and a source of current at the main station, means to cause the said step-by-step switch to be operated by the said source of current under the control of the said circuit interrupter, means to cause the said substation switch to make less than a predetermined number of line circuit interruptions, means to cause said circuit interrupter to make more than the predetermined number of line circuit interruptions, and correcting apparatus for the said step-by-step switch at the main station for restoring the said switch to normal after being actuated under the control of the said switch making less than the predetermined number of circuit interruptions, whereby a subsequent operation of the said circuit interrupter to make more than

the predetermined number of circuit interruptions will move the said switch to the same position that the said switch would be moved were the said switch first moved under the control of the said circuit interrupter with the same actuation of the said circuit interrupter.

14. In an automatic telephone system, the combination with a plurality of telephone lines having numerical designations for calling purposes, a selective switch mechanism at a line interconnecting station under the control of the line apparatus of the lines adapted to interconnect the said lines, substation means for each of the lines for producing circuit interruptions of the said lines to control the said selective switch mechanism, whereby the said selective switch mechanism may operate to connect calling and called telephone lines, and controlling apparatus for the said selective switch mechanism at the line interconnecting station to restore the said selective switch mechanism to normal position after having been moved under the control of less than a predetermined number of line circuit interruptions.

In witness whereof, we hereunto subscribe our names this 4th day of October, A. D. 1916.

HENRY P. CLAUSEN.
CHARLES L. GOODRUM.
